Attorney

UNITED STATES PATENT OFFICE

CHARLES E. GUY, OF NEW ROCHELLE, NEW YORK

ATTACHMENT FOR HATS AND THE LIKE

Application filed November 16, 1927. Serial No. 233,687.

This invention relates to heat insulating attachments for hats.

An important object of the invention is to provide novel heat insulating means adapted 5 to be inserted within a hat to protect the head of the wearer from the action of the rays of the sun.

Another object of the invention is to provide a lining or protector which may be inserted 10 within a hat, cap or the like, and provided with an air space which tends to exclude the heat rays of the sun.

A further object is to provide a lining or protector for hats having means for readily 15 inserting the lining within the hat and securing it thereto.

A further object is to provide a device of the character referred to which includes a body of heat insulating material and which 20 is provided with coacting spaces whereby the head of the wearer of the hat is effectually protected from the action of the rays of the sun.

Other objects and advantages of the invention 25 will be apparent from the following description.

In the drawing I have shown a preferred embodiment of the invention. In this showing,

30 Figure 1 is a central vertical section of a hat with the lining or protector inserted therein,

Figure 2 is a plan view of the assembled lining,

35 Figure 3 is a section on line 3—3 of Figure 2, and

Figure 4 is a view in perspective of a portion of the lining.

Referring to the drawings the numeral 40 10 designates a hat comprising a brim 11, crown 12, hat band 13, and sweat band 14. A lining or protector 15 which forms the subject of the invention, includes a frame 16 made of any light material but preferably 45 of cardboard, is shaped in a manner to conform to the crown of the hat in which it is to be used. This frame is provided with cut out portions 17 and with extensions or tabs 18 connected to the ends of the frame.

50 A lining 19 of cloth or paper, but preferably

of silk is attached to one side of the frame 16 by any desired means such as by sewing but preferably by being glued to the frame. A layer of heat insulating material 20, preferably formed of cork, is glued or otherwise 55 secured, to the opposite side of the frame 16. The layer of heat insulating material 20 is provided with a plurality of projections 21 preferably made of cork. It will be obvious, however, that these projections may 60 be made of a material other than cork as their function is simply to form an air space between the top of the hat and the layer of insulating material.

The protector or lining is attached to the 65 hat or cap most conveniently by holding the hat with its crown extending downwardly, raising up the sweat band all around the hat, bending the projections or tabs 18 at right angles to the plane of the frame 16, inserting 70 the lining within the hat so that the projections or tabs 18 lie adjacent the sides of the crown of the hat, and then bending the sweat band back to its normal position.

From the foregoing it will be apparent that 75 I have provided a lining or protector for a hat which is particularly efficient in protecting the head of the wearer from the rays of the sun. When the lining or protector is in place in the hat the projections 21 contact with 80 the top of the hat thus forming an air space between the crown and the layer of heat insulating material. This air space acts as a very efficient insulating means to prevent the rays of the sun from penetrating through 85 the hat to the head of the wearer. The cut out portions 17 provided in the frame 16 serve the double function of lessening the weight of the lining and also forming additional dead 90 air spaces closed by the heat insulating material on one side and by the silk lining on the opposite side.

Although I have shown and described a preferred form of the invention it is to be 95 understood that changes may be made in the shape, size, and arrangement of parts and in the materials employed without departing from the spirit of the invention or the scope of the subjoined claims.

I claim:

1. A heating insulating attachment for hats and the like comprising a member formed of a pair of layers of material adapted to be arranged in a hat adjacent the top thereof, one only of said layers being provided with cut out portions, the other layer being formed of heat insulating material, and a relatively thin layer secured to the underside of said layer having said cutout portions whereby dead air pockets are provided between said layer of insulating material and said lining.

5 2. A heating insulating attachment for hats and the like comprising a member formed of a pair of layers of material adapted to be arranged in a hat adjacent the top thereof, one of said layers being provided with cut out portions, the other layer being formed of heat insulating material, and means arranged outwardly of the center of said last named layer 10 of material for maintaining it spaced from the top of the hat, and a relatively thin lining secured to one side of said layer having said cutout portions.

15 25 3. A heat insulating attachment for hats and the like comprising a layer of material provided with cut out portions, a layer of lining material secured to one side thereof, a layer of heat insulating material secured to 20 the opposite side thereof, and means for positioning the layers within a hat with the layer of the heat insulating material adjacent the top of the hat and spaced therefrom.

25 35 4. A heat insulating attachment for hats and the like comprising a layer of heat insulating material shaped to conform to the top of the hat and adapted to be arranged in the hat, a plurality of projections carried by one side of said layer and adapted to contact 40 with the top of the hat to form dead air pockets between said layer and the top of said hat, a second layer of material provided with cutout portions arranged adjacent said first named layer, and a lining secured to 45 one side of said second layer to form dead air pockets between said first named layer and said lining.

In testimony whereof I affix my signature.
CHARLES E. GUY.
